US00D861119S

(12) **United States Design Patent** (10) **Patent No.:** **US D861,119 S**
Burrow (45) **Date of Patent:** **** Sep. 24, 2019**

(54) **AMMUNITION CARTRIDGE**(71) Applicant: **TRUE VELOCITY IP HOLDINGS, LLC**, Garland, TX (US)(72) Inventor: **Lonnie Burrow**, Carrollton, TX (US)(73) Assignee: **TRUE VELOCITY IP HOLDINGS, LLC**, Garland, TX (US)(***) Term: **15 Years**(21) Appl. No.: **29/594,100**(22) Filed: **Feb. 15, 2017****Related U.S. Application Data**

(60) Continuation of application No. 15/406,844, filed on Jan. 16, 2017, now Pat. No. 9,933,241, which is a continuation of application No. 14/011,202, filed on Aug. 27, 2013, now Pat. No. 9,546,849, which is a division of application No. 13/292,843, filed on Nov. 9, 2011, now Pat. No. 8,561,543, application No. 29/594,100, which is a continuation of application No. 14/748,508, filed on Jun. 24, 2015, which is a continuation-in-part of application No. 14/011,202, filed on Aug. 27, 2013, now Pat. No. 9,546,849, which is a division of application No. 13/292,843, filed on Nov. 9, 2011, now Pat. No. 8,561,543, application No. 29/594,100, which is a continuation of application No. 14/320,961, filed on Jul. 1, 2014.

(57)

CLAIM

The ornamental design for a cartridge base insert, as shown and described.

DESCRIPTION

FIG. 1 is an isometric view of a mid-body portion of an ammunition cartridge showing my new design.

FIG. 2 is a side view of a mid-body portion of an ammunition cartridge showing my new design.

FIG. 3 is a top view of a mid-body portion of an ammunition cartridge showing my new design.

FIG. 4 is a bottom view of a mid-body portion of an ammunition cartridge showing my new design.

FIG. 5 is a cross sectional view of a mid-body portion of an ammunition cartridge showing my new design; and,

FIG. 6 is an isometric cross sectional view showing the mid-body portion of an ammunition cartridge.

1 Claim, 5 Drawing Sheets# US D861,119 S
